SEWING MACHINE

Philip Ginsberg, New York, N. Y.

Application May 16, 1940, Serial No. 335,460

1 Claim. (Cl. 112—199)

My invention relates to a new and improved sewing machine.

One of the objects of the invention is to improve the type of sewing machine which produces the "straw" or "saddle" stitch.

Another object of the invention is to provide simple parts which can be installed in existing sewing machines of this type.

Another object of the invention is to provide an improved eccentric and link arrangement, whereby the length of the loops of the chain stitch which are produced by this type of machine, can be conveniently regulated so as to produce loops of any desired length.

Other objects of the invention will be set forth in the following description and drawings which illustrate a preferred embodiment thereof, it being understood that the above statement of the objects of my invention is intended to generally explain the same without limiting it in any manner.

Fig. 1 is a bottom plan view of a standard sewing machine to which my improvements have been applied. In this view, part of the representation of member 15 has been omitted, so as to show a part of the representation of shaft 65, which is located above member 15, and which is concealed by member 15 in this view.

Fig. 2 is a side elevation, taken at the left-hand side of Fig. 1.

Fig. 3 is a transverse section, partially in elevation, in a plane which is parallel to the plane of Fig. 2.

Fig. 4 is a sectional view on the line 4—4 of Fig. 3.

Fig. 5 is a sectional view on the line 5—5 of Fig. 1.

Fig. 6 is a sectional view on the line 6—6 of Fig. 5.

Fig. 7 is a sectional view on the line 7—7 of Fig. 3.

The sewing machine is provided with a conventional frame F, the conventional presser foot 2 which is connected to the usual rod 3, and the conventional needle 7 and the conventional hook needle 6, said members 6 and 7 being releasably clamped to the usual needle bar 8, which is reciprocated vertically in the usual manner.

A plate 45a is integral with the frame of the machine. A housing which has depending vertical walls is integral with said plate 45a. The driven power shaft 11 has bearings in said depending vertical walls. The housing is provided with a cover plate 16 which is held to said housing by the screws 17. A shaft 65 is provided

with a gear 14 which meshes with the gear 12 of the driven shaft 11. Said shaft 65 is also provided with suitable bearings in said depending walls of the housing. One of said bearings 65a is shown in Fig. 1. This bearing may be an ordinary bushing. A collar 18 is connected to said shaft 65 by means of the clamping screw 19. One end of the link 20 is connected to the adjacent end face of the collar 18. The means for connecting the link 20 to the collar 18 are identical with the means which are used for connecting said link 20 to the sleeve 18a, which is integral with the disc 26. Said means are shown in detail in Figs. 5 and 6.

The link 20 is provided with a longitudinal slot 21, which has enlargements at the respective ends thereof. A bearing bushing 22 is located in each said enlargement. The legs of the link 20 are urged towards each other by means of pressure screws 32, in order to clamp the bushings 22 in position. A ball 23 is turnably located in each bushing 22. The bushings 22 are sufficiently resilient to enable the balls 23 to be respectively inserted therein by suitable pressure. Each ball 23 has a diametral bore, which is not tapped. Each ball 23 has a respective screw 24, whose shank passes through said untapped bore. The end face of the collar 18 is provided with a tapped recess, whose wall is engaged by the corresponding threaded portion of the shank of a screw 24. A metal spacing washer 25 is located between the end face of the collar 18 and the respective ball 23, and a similar metal spacing washer 25 is located between the circumferential wall of the sleeve 18a and the respective screw 24. These washers 25 prevent binding between the screws 24 and their respective connected parts. Instead of providing a single hole in the end face of the collar 18, three or more such holes could be located along a radial line of said end face, in order to regulate the throw of the link 20, when the shaft 65 and its collar 18 are continuously revolved. The sleeve 18a is turnably mounted upon a stud which is connected to the plate 28, which is clamped to the frame F of the machine by means of screws 29. A holding screw 31 is connected to the wall of a recess of said stud, in order to prevent longitudinal movement of the sleeve 18a relative to said stud.

By means of this construction, the shaft 65 rocks the sleeve 18a and the disc 26, and the amplitude of the rocking movement can be regulated by regulating the throw of the link 20.

Likewise, the ball-and-socket connections between the link 20, and the collar 18 and the

sleeve 18a, make it possible for the shaft 65 to rock the sleeve 18a and its disc 26, even though the axis of oscillation of the sleeve 18a is at right angles to the axis of rotation of the shaft 65.

A link 33 is pivotally connected by a pivot screw 34a to the disc 26. Said link 33 has a slotted head 34, which has resilient legs. These legs are forced towards each other by means of the clamping screw 35, so that the slotted head 34 clamps the shank of a screw 36, which is similar to the screw 24 heretofore described. Said screw 36 is connected by ball-and-socket means to the link 37. The ball-and-socket means which connect the screw 36 to the link 37 are not shown specifically, because they are identical with the ball-and-socket means heretofore described.

The link 37 has a slotted end whose resilient legs are clamped by means of the screw 41 to the turnable pivot pin 40 which is turnably mounted in a bearing sleeve 42, which is fixed to the plate 9. Said plate 9 is connected to frame F by screws 10. A block 43 is clamped to the turnable pivot pin 40, by means of a clamping screw 40a. The sleeve 42 is provided with a shoulder upon which the block 43 abuts. The spreader 44 is clamped to the block 43 by means of the clamping screw 45. The spreader 44 is thus oscillated, and the length of its oscillating movement is regulated by the adjustment of the screw 24 relative to the center of rotation of the end face of the collar 18.

The looper 60 is an integral projection of a plate 61c. This plate 61c is clamped to a supporting plate 61, by means of screws 60d. The plate 61 is provided with a flange 61a at one edge of its rim. The plate 61 is mounted turnably at the end of a stationary rod 15 which extends through the vertical depending walls of the previously mentioned housing. This rod 15 is fixed to said housing by clamping screws or in any suitable manner. The plate 61 is turnably mounted upon a pivot stud 62, which has a threaded shank which engages a tapped recess of the rod 15. A metal spacing washer 62a is also provided so that the plate 61 can turn freely relative to the members 62 and 15. This washer 62a is clearly shown in Fig. 7, and this detail is not shown in the other figures.

The plate 61 is provided with an inclined slot 62b. The shaft 65 has a collar 64 clamped thereto and said collar 64 is provided with an eccentric pin 63 which enters said slot 62b. Therefore, when the shaft 65 is revolved, the plate 61 and the looper plate 61c are oscillated, so as to oscillate the looper 60.

No adjustment is provided for the oscillation of the looper 60, which moves back and forth in a stroke of constant length.

In addition to its bearings in the depending wall of the housing, the shaft 11 has an additional bearing 46, which is integral with the plate 45a which is integral with frame F.

The feed-mechanism is of the conventional type, so that it is not fully illustrated. It is well-known in sewing machines on the market, such as the "Union Special No. 16-200." The feed-dog 4 is operated with the usual "four-motion" movement. It is connected to the bent rod 90, which is fixed by screw 91 to the end-block

of member 55. Said member 55 is pivotally connected at 92 to link 96 which is actuated by an eccentric pin of drive shaft 11, so as to give the feed-dog 4 its up-and-down movement.

5 The longitudinal reciprocating movement of the feed-dog is produced by eccentric 51, whose reduced integral collar 57 is clamped to the drive-shaft 11 by clamping screw 58. The member 55 has the usual follower-shoe 56, which abuts the periphery of eccentric 51, so that when the eccentric 51 is rotated, it produces a longitudinal reciprocating movement of member 55.

The usual means are provided for regulating the length of the feed stroke, in accordance with 15 the length of the loop of the chain stitch. The rod 48 is turnable around its longitudinal axis, and it is clamped to its adjusted position after it has been turned, in the well-known manner. This rod 48 passes through a bearing of the extension 20 47 of the plate 45a. Collar 49 is clamped to rod 48 by clamping screw 50, in order to prevent longitudinal movement of rod 48 in its bearing, in one direction. The arm 52 is fixed to rod 48. Said arm 52 is connected by member 53 to the 25 arm 54, which is integral with member 55. Therefore, by turning rod 48, the distance between the shoe 56 and the surface of eccentric 51 can be regulated, thus regulating the length of the feeding stroke of the feed-dog 4.

The link 96 of the drive shaft moves the feed-dog up and down in the usual manner.

The novel parts can therefore be readily applied to several standard sewing machines, such as the "Union Special No. 16-200," in order to 35 regulate the spreader in a stroke of variable length.

I have shown a preferred embodiment of my invention, but it is clear that numerous changes and omissions can be made without departing 40 from its spirit.

I claim:

A sewing machine comprising a shaft, means 45 adapted to rotate said shaft continuously in the same direction, a first rockable member mounted for oscillation about an axis which is at right angles to the axis of rotation of said shaft, a first link connected to said shaft at a point which is offset relative to the axis of rotation of said shaft, said first link being also connected to said 50 first rockable member to oscillate said first rockable member when the shaft is rotated, the respective connections between said first link and said shaft and also between said first link and said first rockable member including ball-and-socket means adapted to permit the first link to 55 tilt without binding relative to said shaft and relative to said first rockable member, a second rockable member, a spreader connected to said second rockable member, a second link connecting said second rockable member and said first 60 rockable member, said second rockable member being mounted for oscillation about an axis which is parallel to said axis of oscillation of the first rockable member, said second rockable member being oscillated together with the first rockable member, a looper mounted to oscillate, means 65 driven by said shaft and adapted to oscillate the looper.

PHILIP GINSBERG.
